(57) **CLAIM**

The ornamental design for a gas burner assembly as shown and described.

DESCRIPTION

FIG. 1 is a top perspective view of a gas burner assembly showing my new design;

FIG. 2 is a bottom perspective view thereof;

FIG. 3 is a front elevation view thereof;

FIG. 4 is a top plan view thereof;

FIG. 5 is a bottom plan view thereof;

FIG. 6 is a rear elevation view thereof;

FIG. 7 is a side elevation view thereof; and,

FIG. 8 is a side elevation view of the opposite side of FIG. 7.

The portions of the gas burner assembly shown in broken lines form no part of the claimed design.

1 Claim, 8 Drawing Sheets
